UNITED STATES PATENT OFFICE.

HOBART W. MCNEILL, OF OSKALOOSA, IOWA, ASSIGNOR TO THE RASMUSEN CABLE COMPANY, OF CHICAGO, ILLINOIS.

CABLE-RAILWAY APPARATUS.

SPECIFICATION forming part of Letters Patent No. 357,723, dated February 15, 1887.

Application filed April 28, 1886. Serial No. 200,446. (No model.)

To all whom it may concern:

Be it known that I, HOBART W. MCNEILL, a citizen of the United States, residing at Oskaloosa, in the State of Iowa, have invented certain new and useful Improvements in Cable-Railway Apparatus, of which I do declare the following to be a full, clear, and exact description, reference being had to the accompanying drawings, forming part of this specification.

My present invention, while capable of general application to cable railways so far as certain of its features are concerned, has relation particularly to the apparatus of that class of cable railways wherein the propulsion of the car is effected by means of an endless cable traveling within a tube or tunnel between the tracks, said cable being provided at suitable intervals throughout its length with stops adapted to engage with an arm or arms projecting from the car through the slot of the cable-tube, and more especially does my invention relate to the improvement of such apparatus as is used in cable-railway systems of the character set forth in certain Letters Patent granted to C. W. Rasmussen, October 25, 1881, and October 24, 1882.

The objects of my invention are, first, to improve the construction of tube or tunnel for the traveling cable; and to this end my invention consists in the construction of tunnel hereinafter described, and particularly defined in the claims.

In the cable-railway systems shown by the patents of Rasmussen the endless cable was supported upon trucks fixed in such proximity to each other throughout its length as to engage with the arms of spider-wheels or sprocket-wheels that were mounted upon the axles of the car and projecting through the slot of the cable-tube. This construction is objectionable for the reason that it necessitates the use of a multitude of trucks far in excess of the number necessary to support the traveling cable.

Still another object of my present invention is to avoid the use of more trucks than is necessary to sustain the cable; and to this end my invention consists in providing the cable with an improved construction of stop adapted to engage with an arm or arms projecting from

the car; and, secondly, in providing the cable with a series of stops in suitable proximity to engage such arms, and with supporting-trucks at proper distances throughout the length of the cable.

In this connection, also, my invention consists in connecting the trucks which sustain the cable to the stops thereon, instead of directly to the cable itself, so that any lateral strain or deflection of the cable will not affect the movement of the trucks.

A further object of my invention is to improve the construction of truck for sustaining the traveling cable and to provide improved means whereby the lubrication of this truck can be automatically effected.

To this end my invention consists in the novel construction of truck hereinafter described, and particularly defined in the claims at the end of this specification.

A further object of my invention is to provide improved means whereby a cable provided with stops and trucks may be transferred around the curve of a roadway and the drums at the terminals of such roadway.

To this end my invention consists in a series of pulleys located at the curves of the roadway, below the top of the cable-tube, and having their proximities provided with grooves to receive the cable and its stops or trucks.

In this connection my invention also consists in the construction, hereinafter defined, of the pulley or drum for the curve or terminal of the roadway.

Figure 1 is a view in vertical transverse section through the cable-tube, the cable, and one of the cable-trucks. Fig. 2 is a plan view, and Fig. 3 a view in vertical longitudinal section, through a portion of the cable, one of its supporting-trucks, and the adjacent stops. Fig. 4 is a sectional view on line *x* *x* of Fig. 7. Figs. 5 and 6 are plan views of the two sections of which each cable stop is composed. Fig. 7 is an edge view of one of the cable-stops. Fig. 8 is a view in side elevation of the sprocket-wheel and sustaining-frame of the car, showing its position with respect to the stops and trucks of the cable within the tube. Fig. 9 is a plan view of the apparatus at a curve of the roadway, parts being broken away for better

illustration. Fig. 10 is an enlarged plan view of one of the pulleys at a curve of the roadway, showing its position with respect to the cable and its stops and trucks. Fig. 11 is an 5 enlarged view, in vertical transverse section, through the cable-tube and one of the pulleys at a curve of the roadway. Fig. 12 is a plan view, and Fig. 12^a a side view, of a drum at a terminal of the roadway, for reversing the direction of travel of the cable. Fig. 13 is a plan view of the roadway, having the end of the bridge and the adjoining abutment, parts being broken away to illustrate the subjacent mechanism. Fig. 14 is a view in vertical trans- 10 verse section on line *xx* of Fig. 13. Fig. 15 is a view in vertical section on line *yy* of Fig. 13.

The cable-tube, which will rest upon the cross-ties of the track, consists of the bottom plate A, suitably bolted to such cross-ties, and 20 the plates B and B', which constitute the sides and top of the tube. The plate B has its inwardly-bent bottom portion *b* fastened to the bottom plates A by means of suitable bolts or rivets, *b'*, and through the side of this plate B 25 pass the bolts or rivets *b'*, which serve to firmly unite the plate to the angular brackets C, the flanged bottom portions C' of which are bolted, as shown at *c*, to the bottom plate of the tube. The side plate B' is in like manner secured 30 to the bottom plate A by means of suitable bolts or rivets, *b'*, passing through the inwardly-bent bottom portion of this plate, and by means of bolts *b'* is fastened to the bracket-plate C, the angular bottom portion of which 35 is bolted to the base-plate, as shown at *c*. The top B² of the side plate B extends over the greater portion of the top, being separated from the top B³ of the side plate B' a sufficient distance to form the slot D, through 40 which the projecting arms of the spider-wheel W, that is carried by the car, (see Fig. 8,) will pass to engage with the stops on the endless cable. Within the tube, and at the bottom angles of the plates B and B', are placed 45 the rails or ways B⁴, whereon will travel the wheels of the trucks that sustain the endless cable, and in the upper corners of the tube similar rails, B⁵, will be placed to secure the accurate movement of the trucks within the 50 tube. By forming the side plates of the cable-tube with the inwardly-projecting bottom portions I am enabled to firmly secure the tube to its bottom plates, and by means of the brackets C, also bolted to the bottom plate and 55 to the side walls of the tube, to connect the side plates and bottom plates so rigidly together as to avoid all danger of displacement or disarrangement of parts.

In Fig. 8 of the drawings is illustrated the 60 sprocket-wheel and its sustaining-frame above the cable-tube, the arms of this wheel being of sufficient length to engage with the stops upon the cable, these stops being placed in such proximity to each other as to success- 65 sively catch the arms of the sprocket-wheel W when such wheel is free to revolve. The sprocket-wheel, its sustaining-frame, and con-

nection therefor being fully set out and claimed in an application filed by me of even date herewith, and numbered 200,445, need not be 70 herein more fully described.

The stops E upon the endless cable E' are preferably formed of two sections, *e* and *e'*, each section having an open slot from one side to the center, which will permit it to be slipped over the endless cable, and being provided with a seat, *e²*, wherin the cable will rest when the sections have been placed thereon. The section *e* is provided with the dovetailed rib or mortise *e³*, adapted to fit within the correspondingly-dovetailed grooves *e⁴*, formed in the section *e'*, when the two parts of the stops are put together, as shown in Fig. 7, and, if desired, corrugations may be formed upon the faces of the seats *e²* corresponding with the 85 depressions between the strands of the cable, so that when the stops are placed thereon they will be held in fixed position against all danger of slipping. In order to fix the stops upon the cable, the sections *e* and *e'* of each stop 90 will be slipped over the cable from opposite sides thereof in such manner that the dovetail rib of the section *e* shall enter the corresponding seat of the section *e'*, and the stops will then be placed in a power-press and will 95 be forced upon the cable until they firmly bind the same, after which suitable rivets will be passed through the holes *e⁵* from side to side of the stops to securely hold the sections together. By thus forming the stops of sections 100 I am enabled to clamp the stops much more securely to the cable than would be possible were they slipped over the same from the ends. 105 As the stops E serve to engage with the arms of the spider-wheel W, that is carried by the car, it will be seen that these stops must be in such proximity to each other throughout the length of the cable that when the car is stopped 110 the spider-wheel will be continuously revolved by the successive engagement of the stops with its projecting arms.

As in my improved construction the sustaining-trucks of the endless cable do not engage with the projecting arms of the spider-wheel of the car, it is only necessary that these trucks should be placed sufficiently near each other to prevent the sagging of the cable against the bottom of the tube. Each truck 115 consists of a pair of wheels, F, firmly keyed upon an axle, F', so as to turn therewith, and the tread of the wheels is preferably grooved, as shown, and fitted with the rings *f*, of rubber or other sound-deadening material. The axle 120 F' of the truck is journaled within a suitable bearing, *g*, that is formed at the rear portion of the oil-reservoir G, with the bottom of which such bearing communicates by means of suitable ducts. This oil-reservoir G is provided 125 with an orifice to admit the lubricant, such orifice being closed by a suitable cap, *g'*, and from the front end of the reservoir projects the tongue G', which serves to connect the reser- 130

voir, and consequently the truck, with the stop E of the cable. (See Fig. 2.) The cable-stop E in front of each truck is provided with a seat or opening, e^6 , into which the tongue G' will enter, and through this stop is passed the pin or screw e^7 , whereon the tongue G' will be pivotally held.

It will be observed that the slot e^6 of the stop E is somewhat broader than the tongue G', so as to permit of a slight lateral movement of the tongue within the slot, so that any lateral strain upon the cable-stops will not affect the accurate movement of the supporting-trucks. To the top of the journal-bearing g is 15 preferably bolted a strap, g^4 , which loosely encircles the cable.

From the foregoing description it will be seen that the arms projecting from the sprocket-wheel of the car into the slotted cable-tube do 20 not engage with the trucks of the cable, but engage with the series of stops that are firmly clamped thereon; hence the only function of the trucks is to sustain the cable, and the necessity of placing these trucks closely together 25 is thereby avoided.

In Figs. 9, 10, and 11 of the drawings is illustrated my improved mechanism for transferring the cable, its stops, and its sustaining-trucks around the curves of the roadway. At 30 such point of the roadway the cable-tube is enlarged, as shown in Fig. 11, to receive the pulleys or drums H, the axle of each drum being journaled in the top plate I and the bottom plate I' of the tube, and the top plate can 35 be held in position by the brackets I^2 , placed between the pulleys, near the slot of the tube, and by means of a suitable support, I^3 , at the opposite edge of such plate. The several pulleys of the series are placed on a curve with 40 their peripheries as close together as possible, and each pulley is provided upon its periphery with the groove h , adapted to receive the body of the cable, with the seats h^4 , to admit the stops of the cable, with the seats h^5 , for the 45 wheels of the cable-trucks, and seats h^6 , for the arm projecting from the sprocket-wheel of the car. It will be observed that the peripheries of the several pulleys of the series from beginning to end of the curve lie beneath the slot of 50 the cable-tube, and these pulleys will be formed of such diameter as to avoid the necessity of materially increasing the width of the slot along the groove. From this construction it will be seen that the arm projecting from 55 the sprocket wheel of the car remains in the slot of the tube as the car traverses the curve, and is in constant engagement with the stops of the cable. By providing the series of pulleys with the peripheral seats, as shown, the 60 necessity for reversing the position of the cable and its trucks, as heretofore deemed necessary in the Rasmusen system, is avoided.

At the terminals of the roadway, where it is required to reverse the direction of the travel 65 of the cable, I provide a large terminal drum, K, the axle K' of which will be suitably journaled in the top and bottom plates L and L',

and the diameter of which will be preferably equal to the distance between the cable-tubes of the adjoining tracks. The periphery of 70 this drum is provided with the groove k , adapted to receive the endless cable, and with the seats k^1 , to receive the cable-stops, and the seats k^2 , to admit the wheels of the cable-trucks. From this construction it will be seen that in 75 reversing the direction of travel of the cable it is simply required to pass it around the terminal drum, all necessity for twisting the cable incident to turning the pulleys into vertical position, as in the Rasmusen patents, being entirely avoided.

The mechanism for transporting cable-railway cars across bridges is illustrated in Figs. 13, 14, and 15 of the drawings. Upon the abutments at the ends of the bridge and between the parallel tracks of the roadway will be placed a terminal drum, K, around which the main cable will be passed to reverse its direction of travel, this terminal drum being of the construction hereinbefore described, with 85 the addition that from the under side of its rim, studs or pins k^4 will project downwardly from points immediately back of the seats formed in the periphery of the drum to receive the stops upon the cable. At each end 90 of the bridge M a terminal drum, K, of the construction hereinbefore described, will also be provided, and around such terminal drum will extend an endless supplemental cable, M', provided with stops corresponding in number 95 and position with the stops upon the main cable, and provided also, if desired, with sustained trucks, such as those already described. In order to communicate motion to the supplemental or bridge cable from the main cable, 100 and at the same time to provide a means for transferring the car continuously from one cable to the other, I employ the short connecting-cables N, two of such cables being placed upon the abutment at each end of the bridge. 105 These connecting-cables N may be made in the form of sprocket-chains passing over suitable sprocket-wheels, o and o', the axles of which are sustained at the opposite ends of a traveling frame, P. At suitable distances throughout the length of the connecting-chain N are placed the studs or projections n, which engage with the pins k^4 , depending from the rim of the terminal drum K of the main cable and receive motion from such drum as it is 110 revolved by the main cable. From the upper bar, p, of the traveling frame P extend the arms p', to which is connected a flat bar, p², that extends between the drums O and O', and serves as a bearing-support for the connecting-cable N. The under side of the lower bar, p³, is provided with the rack p⁴, as shown, and the outer end of this lower bar is downwardly bent, as at p⁵, and is provided with a friction-wheel, p⁶, whereon the end of the traveling frame is sustained. The rack p⁴ rests 115 upon and engages with the pinion R upon the shaft R', the outer end of this shaft being provided with a miter-gear, r, that meshes with 120

a corresponding miter-gear, r' , on the end of the vertical shaft R' , which is sustained by the standard S , and receives motion through the miter gear-wheels s and S' and the hand-crank 5 S'' . The shaft R' extends across the abutment, and is provided at its opposite end with a pinion, R^3 , which engages with the traveling frame of the adjoining track of the roadway, as seen in Fig. 14. The sprocket-wheel o' , at the outer 10 end of the traveling frame P , has its lower portion formed as a friction-drum, which engages with the friction-drum T , formed beneath the periphery of the terminal drum at each end of the bridge. From the construction 15 as thus defined it will be seen that the connecting-chain N , by reason of the fact that its teeth are engaged with the pins k^4 of the terminal drum of the main cable, is constantly driven by such drum. If, therefore, 20 by turning the crank S'' and the shafts R^2 and R' , the driving frames P are caused to move forward to the position shown in Fig. 15, the friction-drum of the sprocket-wheels o' will be forced into engagement with the friction- 25 drum T of the terminal drum upon the bridge, and will cause this drum to gradually revolve and impart movement to the supplemental or bridge cable M' . It will also be seen that as the projecting arm of the sprocket-wheel of a 30 car is moved along in front of one of the stops of the main cable one of the teeth or studs of the connecting-cable N will pass behind said arm, and will move said arm forward from the main cable until it passes in front of one 35 of the stops of the supplemental or bridge cable, which stop will thus continue to advance the arm of the car across the bridge. When the bridge is to be swung open in order to permit the passage of vessels, the crank S'' 40 will be turned in such manner as to cause the pinions R of the shaft R' to move the traveling frame backward until the drum O' is in such position as to no longer obstruct the swinging of the bridge. By the foregoing construction, the details of which can be varied 45 within wide limits, I am enabled to provide a means whereby cable-cars can be readily transferred across the bridges that may intersect the lines. By providing a friction-gear for 50 communicating movement from the main cable to the supplemental cable of the bridge, I am enabled to gradually start such supplemental cable and thereby avoid all danger of breakage which would be liable to occur in 55 case the entire power of the main cable was exerted at once to overcome the inertia of the supplemental cable and its drums.

It is to be understood that the improvements just described relating to the mechanism for 60 transporting cable-railway cars across bridges forms no part of the subject-matter of the present application, and is not claimed herein, the same being reserved and set forth in a separate application constituting a division 65 hereof.

Having thus described my invention, what

I claim as new, and desire to secure by Letters Patent, is—

1. In cable-railway apparatus, a tube or tunnel for the endless cable, comprising a bottom plate, A , side plates B and B' , mounted upon said bottom plate, and provided with the inner flanges, b , projecting beyond the rails of the tube and adapted to receive bolts, substantially as described. 70
2. In cable-railway apparatus, a propelling-cable having stops throughout its length formed of separate sections, said sections being provided with seats to receive the cable and with overlapping projecting portions connected by bolts extending in the direction of the length of the cable, substantially as described. 75
3. In cable-railway apparatus, a propelling-cable provided with stops formed of separate sections, one of said sections being provided with a mortise and the other section with a groove adapted to receive said mortise, and each of the side sections being provided with a seat for the cable, substantially as described. 80
4. In cable-railway apparatus, a propelling-cable having stops or buttons fixed thereto throughout its length, and provided also at intervals with sustaining-trucks, substantially as described. 85
5. In cable-railway apparatus, a propelling-cable having stops fixed thereto throughout its length, and having sustaining-trucks connected at suitable intervals to certain of said stops of the cable, substantially as described. 90
6. In cable-railway apparatus, the combination, with a propelling-cable having suitable stops fixed thereto throughout its length, and provided at suitable intervals with sustaining-trucks, the axles of which are beneath said cable, and are connected at intervals with certain of the stops thereof, substantially as described. 95
7. In cable-railway apparatus, the combination, with the propelling-cable, of a truck comprising a pair of wheels, an axle for said wheels, a bearing for said axle, and an oil-box in communication with said bearing, substantially as described. 100
8. In cable-railway apparatus, the combination, with the propelling-cable, of a sustaining-truck provided with grooved wheels having thereon rings of sound-deadening material, substantially as described. 105
9. In cable-railway apparatus, the combination, with the propelling-cable, of stops affixed thereto, and sustaining-trucks, said stops and trucks being pivotally connected together, substantially as described. 110
10. In cable-railway apparatus, the combination, with the propelling-cable, of stops affixed thereto, sustaining-trucks connected to said stops and located beneath the cable, and guard-straps extending from the top of said trucks around the cable, substantially as described. 115
11. In cable-railway apparatus, the combi- 120

nation, with a car having a sprocket-wheel carried thereby, of a traveling cable provided throughout its length with stops or buttons adapted to engage with the arms of the 5 sprocket-wheel, and provided also with trucks for supporting said cable, located much farther apart than the stops, substantially as described.

12. In cable-railway apparatus, the combination, with the main cable having stops thereon, of a series of pulleys located between the rails of the track at the curves of the roadway, and having their peripheries provided 15 with grooves or seats to receive the cable and the stops, respectively, substantially as described.

13. In cable-railway apparatus, the combination, with the main cable having stops thereon, of a series of pulleys located at the 20 curves of the roadway, between the rails of the track, and having their peripheries provided with grooves or seats to receive the

cable and the stops, and with spaces for the arm projecting from the car, substantially as described. 25

14. In cable-railway apparatus, the combination, with the main cable having stops thereon, and having sustaining-trucks, of a pulley or drum for changing the direction of the cable, provided with grooves to receive the 30 cable, the stops, and the trucks, substantially as described.

15. In cable-railway apparatus, a drum for reversing the direction of travel of the cable, having in its periphery the groove for the cable, the seats for the cable-stops, the seats for the cable-trucks, and the seats to admit an arm projecting from the car, substantially as described. 35
